TUYÈRE CONSTRUCTION FOR CUPOLAS

Joshua K. Clutts, Detroit, Mich.

Application August 5, 1935, Serial No. 34,656

11 Claims. (Cl. 266—41)

This invention relates to foundry cupolas and particularly to tuyères for such cupolas, and further relates to methods of cupola operation.

For the most efficient and economical operation of a cupola, the air blast delivered by the tuyères should be quite definitely proportioned in volume to the hourly output of molten metal. In many installations, it is necessary from time to time to considerably vary the hourly output, and compensation for such variation has, to some extent, been achieved by pressure control of the blast delivered to or from the tuyères, as by varying the blower speed, or changing the size of the tuyère passages. Such compensation, however, has been far from complete, since for a tuyère zone of fixed diameter, proper penetration of the load by the blast prohibits other than a limited reduction of the blast pressure, and increase of the blast pressure can be effected to only a quite limited extent without detriment to the quality of the melt.

An object of the invention is to provide for varying the blast capacity of cupola tuyères to suit varying requirements in the rate of melting, and for coincidently varying the tuyère length so that proper penetration of the load by the blast will be assured.

Another object is to form a cupola tuyère in sections, whereof a suitable number may be used to extend the tuyère a desired distance toward the cupola axis, said sections predeterminedly varying in air delivery capacity, so as to reduce the volume of the blast proportionately to the inward extent of the tuyères.

A further object is to provide a set of nozzles, differing in capacity, and each corresponding to one of said tuyère sections, the innermost tuyère section, in any installation being adapted to receive the nozzle corresponding to such section, to predeterminedly restrict the delivered blast proportionately to tuyère length.

A still further object is to provide for reducing the volume of air delivered by a tuyère by employing one or more inserts in the working nozzle to reduce the air capacity of the tuyère.

These and various other objects the invention attains by the construction hereinafter described and illustrated in the accompanying drawings, wherein:

50 Fig. 1 is an axial sectional view of the tuyère zone of a cupola having its volume of delivered air reduced in accordance with the invention.

Fig. 2 is a horizontal sectional view of the improved construction as adapted to a lower tuyère 55 of a cupola.

Fig. 3 is a vertical sectional view of the same, taken on the line 3—3 of Fig. 2.

Fig. 4 is a cross sectional view of the same, taken upon the line 4—4 of Fig. 3.

Fig. 5 is a horizontal sectional view of the improved construction, as applied to an upper cupola tuyère.

Fig. 6 is a longitudinal vertical sectional view of the same, taken upon the line 6—6 of Fig. 5.

Fig. 7 is a cross sectional view of the same, 10 taken upon the line 7—7 of Fig. 6.

Fig. 8 is a perspective view, showing complete sets of upper and lower tuyère nozzles.

In these views the reference character 1 designates the usual cylindrical steel shell of a cupola, 15 2, a fire brick lining applied interiorly to said shell, and 3, the usual wind box exteriorly engaging the shell.

It is usual to extend through a cupola wall a lower circular series of relatively large tuyères 4, 20 and an upper circular series of smaller tuyères 5. In the illustrated installation, each lower tuyère comprises several open-ended, box-like sections, of which four are shown, and designated respectively 6, 7, 8, and 9. These sections are adjoined in substantially end to end relation and jointly form an air passage through the lining. The opposite side walls of the several sections are correspondingly convergent and preferably radial 30 to the cupola axis (not shown). The height of the sections 6, 7, 8, and 9 is successively reduced in the order enumerated, and this successive reduction, together with the convergency of their side walls, serves to considerably reduce the cross 35 sectional area of the tuyère, as it extends inwardly.

While the tuyère is illustrated as comprising four of the described sections, it is to be understood that a lesser or greater number of sections 40 may be employed according to the desired reduction of the blast volume.

Within the innermost section of the tuyère, there may be installed an open-ended box-like nozzle 10 predeterminedly limiting the discharging blast, and preferably such nozzle extends beyond the tuyère proper, terminating flush with the inner face of the thickened lining. To facilitate removal or replacement of such nozzle, it is preferred to space it downwardly from the top 50 of the innermost tuyère section and to seal such space with brick or clay or mortar or the like as indicated at 11. Thus molten metal or slag is prevented from locking the nozzle in position, since upon removal of the sealing material, the 55

nozzle can be readily freed by prying it upward with a crow bar or the like.

A tuyère stock 12, arranged exteriorly of the cupola, serves to deliver air from the wind box 3 through the shell 1 to the tuyère section 6, it being understood, however, that such tuyère stocks are rendered superfluous when the wind box directly surrounds the tuyère zone, as is a common construction.

10 Each upper tuyère comprises a set of box-like, open-ended sections 13, 14, 15, and 16, adjoined in an end to end relation to jointly form an air passage through the cupola lining. Within the inner section and removably resting on its bottom, is a box-like open-ended nozzle 17. The outermost tuyère section is preferably formed adjacent to the shell 1 with an upward extension 18 through which air may be delivered to the tuyère from the wind box 3. As in the lower 20 tuyère construction, the side-walls of the upper tuyère sections converge radially of the cupola, and the side walls of the nozzle similarly converge.

Fig. 8 shows two sets of the differently sized 25 nozzles 10 and 17 each nozzle corresponding to one of the tuyère sections, and properly limiting the blast when its corresponding tuyère section is innermost.

Preferably the sections of both the upper and 30 lower tuyères have an interfitting relation adapting them to be readily established in a proper end to end relation. Thus, each section (excepting the outermost) of each tuyère may be formed upon its side walls with a pair of lugs 19 projecting to engage at each side of the outwardly adjacent tuyère section, maintaining accurate alignment.

If it is desired to reduce the tuyère capacities further than is effected by the nozzles 10 and 17, 40 this may be done, as illustrated by inserting in each nozzle a metal plate 20, (or a number thereof) said plates resting freely on the bottom members of the nozzle.

Preferably each tuyère stock 12 will have, in 45 its lower portion an opening normally closed by a door 21, through which opening, the corresponding nozzle 10 may be removed, if desired, while the cupola is in operation. Such a provision is desirable in case any nozzle 10 becomes so 50 clogged, during operation, with slag or metal, as to require cleaning or replacement.

The construction, as described and illustrated 55 adapts a cupola for considerable variation of its blast volume without sacrifice of efficiency. If the interior tuyère zone diameter of the illustrated cupola is originally 65 inches, and it is desired to decrease this to 54 inches, such decrease may be effected by addition of another tier 60 of brick to the lining, and of another section to each of the upper and lower tuyères. By adding another layer of brick and another set of tuyère sections, the interior diameter of the tuyère zone 65 may be further decreased to 44 inches and a still further addition of brick and tuyère sections will establish an interior diameter of 36 inches.

Thus it is apparent that the described construction adapts the volume of blast and the tuyère zone diameter to be so varied as to particularly accommodate the cupola to melts of 70 different tonnage, assuring for any melt a maximum of efficiency and fuel economy. The figures herein given for the various tuyère zone diameters merely illustrate the possibilities, and the tuyère sections and nozzles may be proportioned to establish such diameters as are preferred.

Removal of a nozzle 10 from the inner end of the corresponding tuyère will at times be desirable. Such removal may be accomplished by shoving the nozzle back from its illustrated position so that it may be swung transversely to said 5 position within the wider outer portion of the tuyère. It may then be easily withdrawn through the inner end of the tuyère.

It is essential to note that the described construction, in making provision for a reduction in 10 the hourly output of molten metal, not only predeterminedly cuts down the blast volume but at the same time predeterminedly increases the inward extent of all the tuyères, thus providing the additional penetration of the stock that is made 15 necessary by the reduction in blast volume. Prior provisions for blast reduction have failed to effect a corresponding increase in tuyère length, and they have not adequately reduced the blast because the reduction of the tuyère passages has 20 necessitated an increase of pressure to maintain penetration. Any material surplus of air, with resultant fuel waste is avoided by the present invention.

In addition to adapting a cupola for efficiently 25 delivering molten metal at selective rates, the described tuyère construction reduces upkeep expense, since it is only the inner ends of cupola tuyères that are exposed, at times, to temperatures of detrimental magnitude. The nozzles 10 30 of the described tuyères, therefore, are the only parts requiring occasional replacement, and these parts are comparatively inexpensive.

Fig. 1 shows how the lining thickness is gradually reduced above the tuyères from any increase 35 of diameter at the tuyère zone so as to afford no appreciable lodgement to the stock.

The invention is presented as including all such 40 modifications and changes as come within the scope of the following claims.

What I claim is:

1. A cupola tuyère comprising a plurality of tuyère sections adjoined in the direction of air flow to jointly form an air passage, the flow capacity of said sections being successively reduced in 45 the direction of air flow, and one or more of the sections at the outlet end of the tuyère being removable to increase the capacity of the tuyère.

2. A cupola tuyère as set forth in claim 1, the lateral walls of the tuyère converging in the direction of air flow at substantially the same angle in all of said sections. 50

3. A cupola tuyère as set forth in claim 1, the adjoined ends of said sections having an interfitting relation. 55

4. A cupola tuyère as set forth in claim 1, the height of said sections being successively reduced in the direction of air flow.

5. A cupola tuyère as set forth in claim 1, the lateral walls of the tuyère converging in the direction of air flow at substantially the same angle in all of the sections, and the height of said sections being successively reduced in the direction of air flow. 60

6. In a cupola tuyère as set forth in claim 1, 65 a nozzle inserted in the innermost section, predeterminedly limiting the air flow, and means establishing an approximate air seal between the nozzle and innermost section.

7. In a cupola tuyère as set forth in claim 1, 70 a nozzle removably inserted in one of the tuyère sections and predeterminedly limiting the air flow through the tuyère.

8. In a tuyère construction, the combination 75 with a set of tuyère sections differing in capacity.

and whereof a selective number may be disposed in an end to end relation to form an air passage, of a corresponding set of nozzles, each insertible in the corresponding tuyère section to 5 predeterminedly limit its capacity.

9. The combination with a tuyère having side walls and a flat bottom, of a plate proportioned to fit between said walls on the tuyère bottom to predeterminedly reduce the capacity of the 0 air passage formed by the tuyère.

10. The method of adapting a foundry cupola for efficient operation at less than its maximum melting capacity, consisting in providing the

tuyères of such cupola with inward extensions, and in so thickening the lower portion of the cupola lining as to embed said extensions in the thickened lining.

11. The method of adapting a foundry cupola for efficient operation at less than its maximum melting capacity, consisting in providing the tuyères of such cupola with inward extensions of relatively reduced cross section, in increasing the thickness of the cupola lining throughout 10 the tuyère zone, and gradually reducing such thickness upwardly from the tuyères.

JOSHUA K. CLUTTS.
